FIG. 1 is a front perspective view of the decorative pouch with attachment strap, showing my new design with the flap in a closed position;

FIG. 2 is a rear perspective view thereof;

FIG. 3 is a front perspective view, with the flap shown in an open position;

FIG. 4 is a rear perspective view thereof;

FIG. 5 is a front perspective view shown with the attachment strap;

FIG. 6 is a rear perspective view thereof;

FIG. 7 is a front perspective view, with the attachment strap included and the flap shown in an open position;

FIG. 8 is a rear perspective view thereof; and,

FIG. 9 is a perspective view, shown in use.

The broken lines shown in FIGS. 3 and 7 depicting possible clasps form no part of the claimed design.

The break lines shown in FIGS. 5-8 indicate that the attachment strap is of no particular length and any portion between forms no part of the claimed design.

The broken lines shown in FIG. 9 depict a human form merely to illustrate usage of the subject design and form no part of the claimed design.

The attachment strap is not disclosed in FIGS. 1-4 for convenience of illustration.
